CLAIM

The ornamental design for a lid tray, as shown and described.

DESCRIPTION

FIG. 1 is a front perspective view of a lid tray showing my new design, the lids are shown in broken lines for illustrative purposes only and form no part of the claimed design;

FIG. 2 is a front elevation view thereof;

FIG. 3 is a side elevation view thereof, the opposite side being a mirror image;

FIG. 4 is a top plan view thereof;

FIG. 5 is a bottom plan view of the upper portion shown separately for clarity of illustration;

FIG. 6 is a cross-section view showing the upper and lower portions shown separated; and,

FIG. 7 is a cross-section view showing the upper and lower portions interlocked.
